R. C. LEAKE,
SIGNAL INDICATING AND TRAIN REPORTING ANSWER BACK SYSTEM.
APPLICATION FILED NOV. 23, 1915.

1,355,055.

Patented Oct. 5, 1920.

UNITED STATES PATENT OFFICE.

RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

SIGNAL-INDICATING AND TRAIN-REPORTING ANSWER-BACK SYSTEM.

1,355,055.

Specification of Letters Patent.

Patented Oct. 5, 1920.

Application filed November 23, 1915. Serial No. 62,983.

To all whom it may concern:

Be it known that I, RICHARD C. LEAKE, a citizen of the United States, and resident of the city of Rochester, in the county of Monroe and State of New York, have invented a new and useful Signal-Indicating and Train-Reporting Answer-Back System, of which the following is a specification.

This invention relates to signaling systems for railroads, and more particularly to apparatus and circuits adapted to be used in connection with telephone train despatching systems for controlling from a central station, or train despatcher's office, signals and automatic train reporting devices at distant points along the railroad.

The ultimate objects sought and attained by this invention is to provide at reasonable cost of installation a system of mechanisms or appliances which automatically provide practically all the facilities of a train order station without the expense of human agents or operators who may be dispensed with, hence the invention may advantageously be adopted at any desired place or places along a railway line where the expense of such agents may prohibit their employment.

The various objects and functions and advantages of this invention will more fully appear in the following detailed description, and the novelty of the invention will be particularly pointed out in the appended claims.

Reference is made to the accompanying sheet of drawing forming part of this specification and diagrammatically representing the invention.

In the drawings, the letter A indicates generally the answer-back or signal sending mechanism which includes an electromagnetic device or motor B. The letter C indicates generally a polarized relay.

The letter D, generally indicates a selector device, such as is shown and described in detail in U. S. Patent No. 1,118,120, granted November 24th, 1914, to Maurice F. Geer and Richard C. Leake. The letter E, generally indicates a simplified form of equipment at the train despatcher's office for operating the four groups of contacts of the

selectors at the various way stations and for receiving the answer back indications. The key and switch are shown because they are a simpler and more easily described means for sending the electric code impulses suitable for controlling the selector contacts at the several local stations than the calling keys preferably used and such as are described in U. S. Patent No. 1,105,766, granted August 4th, 1914, to Maurice F. Geer and Richard C. Leake. The letter G, indicates an insulated track section of a railway track. The letters H, I, indicate other insulated track sections which are respectively connected by pairs of wires j, j', and k, k', with mechanisms grouped at other way stations J, K, and similar to those shown, for track section G, and which are likewise in circuit with the telephone line F. The letter L, indicates a semaphore signal for track section G. Associated with each track section, as track section G, are two relays M and O. The relay O, by reason of the fact that it has as a principal function the control of a signal, is conveniently termed the signal relay and the relay N, because it has as a principal function, to control parts of the system for reporting train movements, is conveniently termed the "O S" relay. The expression "O S" being chosen because it has been common practice in telegraph train despatching to report a train by sending in the Morse code the letters "O S" followed by the train number.

The answer wheel 1 is a toothed ring revolvably held by rollers 2, engaging its inner track 3, which has a notch 4, into and out of which ride two insulating rollers 5, 6, respectively secured to the free ends of two conductive arms 7, 8, pivoted to two binding posts 9, 10. An insulated conductive contact 11, is disposed centrally within the wheel 1, and is adapted to be engaged by either of two elastic contacts 12, 13, carried by the respective arms 7, 8, as determined by the riding of the respective arm rollers 5, 6, into and out of the wheel notch 4. The answer wheel has a series of peripheral teeth some of which are cut away at the 100

ends, and the full length and shorter teeth may be relatively arranged to provide for closing by the long teeth a series of electric circuits causing distinctive code clicks or sounds at the train despatcher's telephone. As shown the answer wheel 1, when rotated once clockwise will assure three distinctive series of "three-two" clicks, and when rotated once counter-clockwise will assure three distinctive series of reverse order "two-three" clicks at the telephone. As the answer wheel rotates, its series of long teeth depress an insulating roller 14, carried by a conductive arm 15, fulcrumed to a binding post 16. The arm 15 carries a head-plate 17, having contacts 18, 19, and an insulating roller 20. To respective binding posts 21, 22, 23, 24, are secured elastic contact plates 25, 26, 27, 28, respectively carrying contacts 29, 30, 31, 32. As the arm 15, and its plate 17, are together depressed by the longer teeth 33 of the answer-wheel 1, the three opposed pairs of contacts 18—29, 19—30, 31—32, are respectively closed to establish certain hereinafter named telephone circuits, and as each long tooth 33, passes beyond the roller 14, the contact arm 15, and contact plates 25, 26, 27, 28, resume normal positions against stops 34, and then the three pairs of contacts are separated to break said circuits. The short teeth 35 of the said answer-wheel 1, pass the roller 14, without circuit closing effect.

The answer wheel is rotated directly by two pawls 36, 37, which engage the teeth 33, 35 thereon, and are pivoted to the upright arm 38, of an armature 39, the opposite ends of which oppose the poles 40, 41, of two magnets having respective wire windings or coils 42, 43. This armature 39 is normally restored by a suitable means (not shown) to the central or intermediate position shown in the drawing. On a shaft 44, is fixed a control armature 45, the narrower upper end of which is attracted by either energized magnet pole 40, 41. Shaft 44, also fixedly carries an arm 46, the head of which is adapted to strike either one of two resilient contacts 47, 48, and momentarily separate them from relatively fixed contacts 49, 50.

During clockwise rotation of the answer wheel 1, the magnet 40—42, is energized and swings control armature 45 in direction of arrow x, until the head 46, on the armature shaft 44, moves contact 47, from contact 49, thereby momentarily breaking the magnet energizing circuit which permits parts 45, 46, by gravity aided by the resiliency of contact 47, to resume their normal or central position and thus remake this circuit which again is likewise broken, and so on intermittently until the answer wheel operating circuit is finally broken; and when the wheel is turned counter-clockwise the other mag-

net 41—43, is energized and swings armature 45, in direction of arrow y, until the head 46, moves contact 48, from contact 50, to momentarily break the energizing circuit, and permit readjustment of parts 45, 46, to their normal or central position to remake this circuit. Energizing either magnet attracts armature 38—39, and actuates the pawls 36, 37, to rotate the answer wheel 1 in opposite direction, for purposes hereinafter more fully described. During clockwise rotation of the answer wheel both contacts 12, 13, engage contact 11, for most of the time, but 12, alone is active while 13, is inert, and during counter-clockwise rotation of the answer wheel the contacts 12, 13, likewise engage central contact 11, but now 13, alone is active while 12, is inert.

The polarized selector relay C, is preferably placed at a local station, and comprises two pole-pieces 52, 53, respectively having surrounding wire coils 54, 55. A pivoted armature 56, is selectively attracted by either pole 52, 53, and is held in its selected position, by the action of the permanent magnet (not shown), and as shown has a stem 57, 58, adapted to engage either of two contacts,

The selector D, comprises two magnets respectively having wire coils 59, 60, connected in series at one end by a wire 61, and connected at their other ends to hereinafter named circuit wires. The detail construction and operation of the selector is shown in the Patent No. 1,118,120, granted to Maurice F. Geer and Richard C. Leake, herein referred to, and for a clear understanding of this invention it is sufficient to know that the selector D may be controlled by the train despatcher to move the button 63 down against any one of four groups of contacts respectively marked H I, C I, S T, O S. The H I, contact group comprises three resilient fingers 64, 65, 66, the one 64, being normally separated from fingers 65, 66, but engaging both when operated. The C I contact group comprises three fingers including a finger 67, which normally engages a second finger 68, but is separated from a third finger 69, and when operated the fingers 67, 68, are separated and the fingers 67, 69, are engaged. The S T contact group likewise comprises three fingers 70, 71, 72, the one 70, normally engaging finger 71, while separated from finger 72, and when operated the fingers 70, 71, are separated and the fingers 70, 72, are engaged. The O S contact group comprises three resilient fingers 73, 74, 75, the one 73, being normally separated from fingers 74, 75, but engaging both when operated. Each contact group of each selector D, is operative only by a certain combination of positive and negative impulses sent through the coils 59, 60, and these impulse combinations differ

for the different selectors used to make or break certain electric circuits at different local stations or places along a railway line. The selector contacts 64 to 75, are connected 5 to hereinafter named circuit wires.

The illustrated train despatcher's equipment E, comprises a pole-changer having two pivoted switches 76—77, coupled for movement together and adjustable to three 10 contacts 78, 79, 80. A wire 81, connects contact 79, with the negative pole of a battery 82, the positive pole of which is connected by wire 83, to the contact 80, and a wire 84, connects the contact 78, with the wire 83. 15 The fulcrum of switch 76, connects by a wire 85, with the telephone line wire 86, and the other line wire 87, is connected by a wire 88, to the telegrapher's key 89, making and breaking circuit at a contact 90, which is 20 connected by wire 91, with the fulcrum of switch 77. The telephone receiver 92, is connected in bridge by wires 93, 94, to the respective wires 85, 88, in which are interposed impedance coils or devices 95, 96, sub- 25 duing or minimizing at the receiver 92, the click sounds of the key 89, thereby avoiding disagreeable knocking at the train despatcher's ear. When the switches 76—77, are adjusted to the left hand as shown, electric 30 impulses of one polarity may be impressed upon line wires 86, 87, from battery 82, by operating the key 89, and when the switches are adjusted to the right hand, impulses of opposite polarity thus may be impressed 35 upon the telephone line. It will be remembered that like reverse impulses are automatically impressed upon the telephone line when the despatcher operates calling keys such as shown in above named Patent No. 40 1,105,766.

The track relay M, comprises a wire coil 97, having opposite ends connecting by respective wires 98, 99, with the respective rails 100, 101, of the track section G, and 45 these rails are in circuit by wires 102, 103, with opposite poles of the track section energizing battery 104. Relay M, has one armature 105, which may be attracted by the energized relay coil 97, to a front contact 50 106, from which it falls when the coil is energized. The O S relay N, comprises a wire coil 107, and five contact fingers, conveniently termed armatures 108, 109, 110, 111, 112. When coil 107 is energized all five 55 armatures are lifted, but only two, or 108, 110, respectively engage front contacts 113, 114, and when coil 107, is deenergized all five armatures gravitally drop and then four, or 109, 110, 111, 112, respectively engage back contacts 115, 116, 117, 118. The 60 signal relay O comprises a coil 119, and five contact fingers, conveniently termed armatures 120, 121, 122, 123, 124. When coil 119, is energized all five armatures are lifted

and three or 120, 121, 123, respectively engage front contacts 125, 126, 127, and when coil 119, is deenergized all five armatures drop and then three, or 122, 123, 124, engage respective back contacts 128, 129, 130. The signal L is shown coupled by a rod 131, 70 to a circuit breaker 132, furnished at 133, so as to electrically connect with either of two contacts 134, 135.

A brief preliminary schedule of the eighteen 75 employed and hereinafter traced electric circuits is given as follows:

1st. Through operated H 1 contacts to the coil 119, picking up armatures of signal relay O.

2nd. Stick-up through coil 119, for signal 80 relay O.

3rd. Energizes signal motor and moves signal from horizontal to vertical position.

4th. Energizes answer-back magnet coil 42, and turns the answer wheel one tooth or 85 step clockwise.

5th. Operates through answer-back arm 7, and rotates the answer wheel clockwise until roller 5 drops into notch 4.

6th. Includes selector relay armature 56, 90 and contact 57 and causes continuous clockwise rotation of the answer-wheel.

7th. Through operated S T contacts and stops clockwise rotation of the answer wheel.

8th. Through operated C L contacts and 95 breaks 2nd stick circuit and turns the answer wheel one tooth counter-clockwise.

9th. Operates through answer-back arm 8, and rotates the answer wheel counter-clockwise until roller 6 drops into the notch 4. 100

10th. Includes selector relay armature 56 and contact 58 and causes continuous counter-clockwise rotation of the answer-wheel.

11th. Through operated S T contacts and 105 stops counter-clockwise rotation of the answer wheel.

12th. Through operated O S contacts and energizes O S relay N, for "setting" it to later assure report of train arrival at track section G. 110

13th. Stick-up through coil 107, for the O S relay N.

14th. Operates the answer wheel one tooth or step clockwise when O S contacts are closed. 115

15th. Operates through answer-back coil 42, to continue clockwise turning of the answer wheel for two-thirds of a revolution to attest "setting" of O S relay N.

16th. Operates through selector relay 120 coil 55, to shift selector relay armature 56, to contact 58, to later cause continuous counter-clockwise rotation of the answer wheel for attesting train arrival at track section G. 120

17th. Primary induction coil answer-back 125 attest circuit.

18th. Secondary induction coil answer-back attest circuit.

The answer back attests are distinguishable as follows:

Signal moved to vertical position, "three-two" clicks continuously.

5 Verifying signal at vertical position, "three-two" clicks, three times.

Signal returned to horizontal position, "two-three" clicks continuously.

Verifying signal at horizontal position, 10 "two-three" clicks, three times.

"Setting" the O S relay N, "three-two" clicks, twice.

Verifying O S relay "setting," "three-two" clicks, three times.

15 Train arrival at track section G, "two-three" clicks continuously.

Annuling O S relay setting before train arrival, "two-three" clicks, twice.

The aforesaid eighteen electric circuits 20 are traced as follows: The

First circuit

is from positive battery P, wires 136, 137, 25 operated H I contacts 64, 65, wires 138, 139, coil 119, of signal relay O, wire 140, armature 109, of deenergized O S relay N, back contact 115, and wires 141, 142, 143, to negative battery P. The

Second circuit

30 is from positive battery P, wires 136, 137, 144, normally closed C L contacts 67, 68, wire 145, front contact 125, armature 120, of energized signal relay O, wires 146, 139, 35 coil 119, of relay O, wire 140, armature 109, of deenergized O S relay N, contact 115, and wires 141, 142, 143, to negative battery P. The

Third circuit

40 is from positive battery P, wires 136, 137, 147, front contact 126, armature 121, of energized signal relay O, wire 148, motor of signal L, and wires 149, 150, 151, 142, 143, to negative battery P. The

Fourth circuit

is from positive battery P, wires 136, 137, 50 operated H I contacts 64, 66, wire 152, back contact 118, armature 112, of deenergized O S relay N, wires 153, 154, answer-back coil 42, wire 155, armature 110, of relay N, back contact 116, wire 156, post 135, moved circuit breaker 132, and wires 157, 150, 151, 142, 143, to negative battery P. The

Fifth circuit

is from positive battery P, wires 136, 137, 55 158, contacts 11, 12, arm 7, post 9, wires 159, 160, resilient contact 47, contact 49, wires 161, 154, answer-back coil 42, wire 155, armature 110, of deenergized O S relay N, back contact 116, wire 156, post 135, moved signal circuit breaker 132, and wires 157,

150, 151, 142, 143, to negative battery P. The

Sixth circuit

is from positive battery P, wires 136, 137, 70 162, selector relay armature 56, contact 57, wires 163, 160, and thence as in fifth circuit, through resilient contact 47, contact 49, wires 161, 154, answer-back coil 42, wire 155, armature 110 of deenergized O S relay N, back contact 116, wire 156, post 135, moved signal circuit breaker 132, and wires 157, 150, 151, 142, 143, to negative battery P. The

Seventh circuit

is from positive battery P, wires 136, 137, 80 164, operated S T contacts 70, 72, wire 165, front contact 127, of energized signal relay O, armature 123, of relay O, wires 166, 167, selector relay coil 55, and wires 168, 143, to negative battery P. The

85

Eighth circuit

is from positive battery P, wires 136, 137, 90 144, operated C L contacts 67, 69, wires 169, 170, answer-back coil 43, wire 171, back contact 117, armature 111, of deenergized O S relay N, wire 172, post 134, returned signal circuit breaker 132, and wires 157, 150, 151, 142, 143, to negative battery P. The

95

Ninth circuit

is from positive battery P, wires 136, 137, 100 158, contacts 11, 13, arm 8, post 10, wire 173, resilient contact 48, contact 50, wires 174, 170, answer-back coil 43, wire 171, back contact 117, armature 111, of deenergized O S relay N, wire 172, post 134, returned signal circuit breaker 132, and wires 157, 150, 151, 142, 143, to negative battery P. The

105

Tenth circuit

is from positive battery P, wires 136, 137, 110 162, selector relay armature 56, contact 58, wire 175, post 10, and thence as in ninth circuit, through wire 173, resilient contact 48, contact 50, wires 174, 170, answer-back coil 43, wire 171, back contact 117, armature 111, of deenergized O S relay N, wire 172, post 134, returned signal circuit breaker 132, and wires 157, 150, 151, 142, 143, to negative battery P. The

110

Eleventh circuit

is from positive battery P, wires 136, 137, 120 164, operated S T contacts 70, 72, wire 165, 12 back contact 128, armature 122, of deenergized signal relay O, wire 201, selector relay coil 54, and wires 168, 143, to negative battery P. The

120

Twelfth circuit

is from positive battery P, wires 136, 137, 125 176, operated O S contacts 73, 75, wires 177,

166, armature 123, of deenergized signal relay O, back contact 129, of relay O, wire 178, armature 105, of energized track relay M, front contact 106, wire 179, coil 107, of O S 5 relay N, and wires 180, 151, 142, 143, to negative battery P. The

Thirteenth circuit

is from positive battery P, wires 136, 137, 10 164, normally closed S T contacts 70, 71, wire 181, front contact 113, armature 108, of energized O S relay N, wires 182, 178, armature 105, of energized track relay M, front contact 106, wire 179, coil 107, of energized 15 O S relay N, and wires 180, 151, 142, 143, to negative battery P. The

Fourteenth circuit

is from positive battery P, wires 136, 137, 20 176, operated O S contacts 73, 74, wire 183, back contact 130, armature 124, of deenergized signal relay O, wires 184, 153, 154, answer-back coil 42, wire 155, armature 110, of energized O S relay N, front contact 114, 25 and wires 141, 142, 143, to negative battery P. The

Fifteenth circuit

is from positive battery P, wires 136, 137, 30 158, contacts 11, 12, arm 7, post 9, wires 159, 160, resilient contact 47, contact 49, wires 161, 154, answer-back coil 42, wire 155, armature 110, of energized O S relay N, front contact 114, and wires 141, 142, 143, 35 to negative battery P. The

Sixteenth circuit

is from positive battery P, wires 136, 137, 176, operated O S contacts 73, 75, wires 177, 40 167, selector relay coil 55, and wires 168, 143, to negative battery P.

There are two additional circuits directly assuring the answer back attests at the train despatcher's telephone and including a

Seventeenth circuit

from positive battery P, wires 136, 185, the primary winding 186, of an induction coil, wire 187, post 22, plate 26, its contact 30, contact 19, on headplate 17, and its other 50 contact 18 to contact 29, on plate 25, through plate 25, to post 21, and by wire 188, to such portion of the battery P, as shall assure passage of only so much of its energy as may be necessary for completing the answer back circuits to give clearly audible click attests at the telephone receiver 92, which is included in an

Eighteenth circuit

60 induced by making and breaking the seventeenth circuit and traced from the secondary winding 189, of the induction coil through wire 187, post 22, plate 26, contacts 30, 19, headplate 17, arm 15, its fulcrum post 16,

wires 190, 191, to telephone line wire 87, 65 and thence by wires 88, 94, to telephone receiver 92, and by wires 93, 85, to the other telephone line wire 86, and thence by wires 192, 193, to post 24, plate 28, contacts 32, 31, plate 27, post 23, wire 194, condenser 70 195, and wire 196, back to the secondary induction coil 189.

The selector coil circuit wires 197, 198, are respectively connected to the answer-back line wires 190, 193, at points behind a lightning arrester 199, grounded at 200. Current thus is taken from the telephone line wires 86, 87, for energizing the selector armature operating coils 59, 60, for actuating the four groups H I, C L, S T, O S, of selector contacts. When the train despatcher operates the switch 77-78, and telegrapher's key 89, or equivalent calling keys, he impresses like positive and negative impulses upon the selectors D, at all distant 85 stations of a railway line but the selector at only one station at which he desires to actuate a signal, or from which he wishes an O S of a particular passing train, will respond and close a circuit through the corresponding selector contact group to assure the desired operative result. The insulation at the ends of track sections G, H, I, is indicated by the numeral 202.

Should the train despatcher at a central 95 or terminal station wish to set the distant horizontally adjusted signal L, to vertical position, and assuming that both the O S relay N, and signal relay O, are normally deenergized, the despatcher will, by the key 100 and switch devices E, or by an equivalent calling key, impress on the telephone line F, the electric impulses necessary to briefly actuate the H I, contact group of the selector D, at the desired distant track section G, 105 thereby closing the aforesaid first electric circuit which by passing through the coil 119, of the signal relay O, energizes this relay and lifts its armatures to opposed front contacts thereby closing the 110 aforesaid second circuit which sticks up the armatures notwithstanding automatic opening of the H I contacts which remain closed for but a few seconds. The third circuit made simultaneously with the first and second circuits, passes through the signal motor and moves the signal from horizontal to vertical position, thereby causing rod 131, to swing signal circuit breaker 132, from contact 134, to contact 135, thereby making the 120 aforesaid fourth, fifth and sixth circuits. The fourth circuit by energizing the answer-back magnet coil 42, turns the answer wheel 1, one tooth or step clockwise in direction of arrow r, by the pawl 36, and then locks 125 the answer wheel 1 until after the H I contacts open so as to delay the transmission of the answer-back impulses until after the

line is cleared to open the contacts H I, in order that the current change in the line circuit, occurring when the H I contacts are opened, will not mingle with the answer-back impulses and cause confusion. The sixth circuit causes continuous clockwise rotation of the wheel, thereby causing its teeth series 33, to intermittently close the subjacent pairs of contacts 18—29, 19—30, 31—32, 5 to make the aforesaid seventeenth and eighteenth circuits and thus assure continuous series of "three-two" click sounds at the despatcher's telephone 92, informing the despatcher that the signal L, for track section G, has moved from horizontal to vertical position. When this "three-two" click attest is clearly understood the despatcher stops it by stopping clockwise rotation of the answer wheel, which he does by actuating the devices E, or an equivalent selector key, to cause operation of the S T group of contacts of selector D, thereby temporarily making the aforesaid seventh circuit which energizes the selector relay coil 55, thereby 10 shifting the selector relay armature 56, from contact 57, to contact 58, thus breaking the sixth circuit but leaving the fifth active to further rotate the answer wheel clockwise until the roller 5, on the active contact 12, 15 enters the wheel notch 4, and thus separates contacts 11, 12, to break the fifth circuit to stop the answer wheel.

Should the same or a succeeding train despatcher for any reason wish to obtain a later verifying attest of movement of signal L, to vertical position, he may do this by simply causing operation of the H I contacts, thereby again closing the fourth and fifth circuits to again rotate the answer 20 wheel 1, in the same clockwise direction by intermittently energizing the magnet coil 42, and while contact 12 is active and contact 13, is inert at the post 11. As the selector relay armature 56, had previously been moved by the seventh circuit away from contact 57, the sixth circuit through 56, 57, is not established and therefore cannot urge the answer wheel notch 4, past the roller 5, after the roller enters the notch. Consequently, for verifying attest purpose, the answer wheel will make only one complete clockwise revolution under influence of the fifth circuit and will stop when the roller 5, 25 enters the wheel notch 4. This one clockwise revolution of wheel 1, gives three verifying "three-two" click answer back attest at the telephone 92, to reassure the train despatcher that the signal L, is correctly set at vertical position. If this one triple verifying attest be insufficient, the H I contacts 30 may again be operated to likewise cause another full clockwise revolution of the answer wheel and thus assure another triple verifying "three-two" click answer back attest at

the telephone. These verifying attest are obtainable independently of operation of the signal, which meanwhile had not changed its vertical position.

When the train despatcher wishes to return or reset the signal to normal horizontal position, he operates the key and switch devices E, or an equivalent calling key, to operate the C L contact group of selector D, thereby separating or opening the normally closed C L contacts 67, 68, through 75 which the existing second or stick circuit for the armatures of signal relay O is made, and thus causing separation of armature 120, from front contact 125, thereby deenergizing signal relay O, and allowing all of 80 its armatures to drop. The fall of armature 121, from front contact 126, breaks the third signal motor operating circuit which is holding the signal L, at vertical position, and as the signal is no longer electrically 85 so held, it gravitally falls to the illustrated horizontal position and in so doing moves signal circuit breaker 132, from contact 135, to its contact 134. The ninth and tenth circuits are now established, the armature 56 90 of the selector relay C being now in the dotted line position and causes continuous counter-clockwise rotation of the answer wheel 1, in direction of arrow 1. This rotation of the answer wheel 1 causes its teeth 95 33, to intermittently close the subjacent pairs of contacts 18—29, 19—30, 31—32, to remake the aforesaid seventeenth and eighteenth circuits and assure continuous series of reverse order "two-three" clicks at the 100 despatcher's telephone 92, which tells the despatcher that the distant signal L, for track section G, has returned to the desired normal horizontal position. When this "two-three" click attest is fully understood, 105 the despatcher stops it by stopping counter-clockwise rotation of the answer-wheel, which he does by actuating the key and switch devices E, or an equivalent calling key, to cause operation of the S T selector 110 contacts thereby making the hereinabove named eleventh circuit which, by energizing the selector relay coil 54, and returning its armature 56, to the contact 57, breaks the tenth circuit at the contact 58. When the 115 tenth circuit is broken as aforesaid by shifting of armature 56, from contact 58, the ninth circuit through answer-back coil 43, remained active to further rotate the answer wheel counter-clockwise until the roller 6, 120 on the active contact 13, enters the wheel notch 4, and thus separates contacts 11, 13, to break the ninth circuit and stop the wheel and thus stop the "two-three" click attest of signal adjustment to horizontal position, 125 and all the herein-described mechanisms and parts thereof now have normal relative positions shown in the drawing.

Should the same or a succeeding train despatcher for any reason wish to obtain a later verifying attest of return movement of the signal L, to horizontal position, he may do this by simply causing operation of the C L contacts, thereby again closing the eighth and ninth circuits to again rotate the answer wheel 1, in the same counter-clockwise direction by intermittently energizing the magnet coil 43, and while contact 13, is active and contact 12, is inert at the post 11. As the selector relay armature 56, had previously been moved by the eleventh circuit away from contact 58, the tenth circuit, through 56, 58, is not established and therefore cannot urge the answer wheel notch 4, past the roller 6, and consequently, for verifying attest purpose the answer wheel will make but one full counter-clockwise revolution under influence of the ninth circuit and will stop when the roller 6, enters the wheel notch 4. This one counter-clockwise revolution of wheel 1, assures three verifying "two-three" click answer back attest at the telephone 92, to reassure the train despatcher that the signal is in horizontal position. If this one triple verifying attest be insufficient the C L contacts may again be actuated to likewise cause another triple "two-three" click attest at the telephone. These verifying attest of horizontal position of the signal may be obtained without moving the signal to vertical position. The aforesaid eighth and ninth circuits causing counter-clockwise rotation of the answer wheel assuring the original and verifying attest of adjustment of the signal from vertical to horizontal position, are made through the armature 111, and back contact 117, of the deenergized O S relay N, consequently neither of these attest can be obtained unless the relay N be in normal deenergized condition, and the receipt of said attest or attest by the train despatcher assures him that the O S relay N, is deenergized and that the signal L, is at normal horizontal position.

Should the train despatcher wish an O S report of arrival of any particular train at distant track section G, he may obtain it by operating the key and switch devices E, or an equivalent calling key, to impress on the telephone line F, the electric impulses necessary to briefly actuate the O S contact group of selector D, thereby assuring making of the aforesaid twelfth circuit. The twelfth circuit by passing through coil 107, of the O S relay N, energizes this relay and lifts its armatures 108, 110, to front contacts 113, 114, and the thirteenth circuit sticks up the armatures after the O S contacts open, thereby "setting" relay N, to assure later O S report of arrival of the train at track section G, and also closing the fourteenth and fifteenth circuits. At the time the operation of conditioning the apparatus to give a report of the passing of a train, now being described, is commenced, the parts are in the position shown in the drawing. The closing of the O S contacts 73 and 75 establishes the sixteenth circuit which causes the armature 56 to shift to its dotted line position. This prevents the answer wheel being rotated continuously clockwise but does not prevent clockwise rotation of the answer wheel by the fifteenth circuit. The reason why the fifteenth circuit now may rotate the answer wheel clockwise is that this circuit does not pass through the selector relay armature 56, which now may remain at contact 58, without interfering with operation of the fifteenth circuit which passes through and energizes answer-back magnet coil 42. The fourteenth circuit turns the answer wheel one tooth or step clockwise and then locks the wheel until after the O S contacts open, in order to avoid confusion of the answer back impulses, as explained hereinbefore. Since the roller 6, of contact 13, is within the wheel notch 4, it requires only a two-thirds clockwise rotation of the wheel to carry its notch 4, around to where the roller 5, will enter it and thus separate contacts 11, 12, to break the fifteenth circuit and thus automatically stop the wheel after it had turned clockwise for only two-thirds of a revolution. During this movement the wheel teeth 33, actuated the three subjacent pairs of contacts to cause two distinctive "three-two" answer back clicks at the train despatcher's telephone 92, informing him that the O S relay N has been energized and the whole answer back mechanism properly placed in condition to report to the despatcher the arrival of the next train at track section G. At any time before such train arrival the same or a succeeding train despatcher may obtain one or more verifying attest of the aforesaid "setting" of relay N, by simply causing operation of the O S selector contacts thereby again closing the aforesaid fourteenth and fifteenth circuits to again energize answer-back coil 42, and turn the answer wheel clockwise. As the roller 5, is in the wheel notch 4, when the answer wheel starts, the answer wheel will make one complete clockwise revolution and will automatically stop when the roller 5, next enters the notch to separate contacts 11, 12. During such wheel rotation its teeth 33, actuate the three subjacent pairs of contacts to assure three distinctive "three-two" answer back clicks at the telephone 92, thereby reassuring the train despatcher that the O S relay N, is properly "set" to report to him the arrival of the next train at track section G. If this one triple verifying attest be insufficient he may obtain another like attest by

again causing operation of the O S contacts. The aforesaid fourteenth circuit having been made through the answer back coil 42, and the back contact 130, and dropped armature 124, of deenergized signal relay O, it is obvious that verifying attests of "setting" of the O S relay N could not have been received by the train despatcher unless the signal relay O, was deenergized and the signal L, was at normal horizontal position.

When the first passing train arrives at track section G, the track circuit through battery 104, and the coil 97, of track relay M, is short-circuited through the track rails and the car wheels and axles to an extent permitting the armature 105, of relay M, to gravitally drop from its front contact 106. The dropping of track relay armature 105, from contact 106, breaks the existing thirteenth stick circuit and therefore the armatures of the now deenergized O S relay N, gravitally drop. The simultaneous dropping of all armatures 108 to 112, of deenergized O S relay N, establishes the ninth and tenth circuits which also pass through the contact 134, and the signal circuit breaker 132, when the signal L, is in the illustrated normal horizontal position. It will be remembered that the aforesaid sixteenth circuit made by operating the O S contacts energized the selector relay coil 55, thus shifting the selector relay armature 56, to the contact 58. It therefore follows that when the O S relay N, is deenergized by arrival of the train on track section G, and the aforesaid ninth and tenth circuits are thereby established the answer wheel 1, will be continuously rotated counter-clockwise, and will actuate the three subjacent pairs of contacts to assure a continuous series of "two-three" answer back clicks at the train despatcher's telephone 92, advising him of the arrival of the train at distant track section G. When the attest is fully understood the despatcher stops it by actuating the key and switch devices E, or an equivalent selector key, to establish the eleventh circuit and cause operation of the S T contact group thereby shifting selector relay armature 56, from contact 58, to contact 57, and breaking the existing tenth circuit at 56, 58, and leaving the ninth circuit active to further rotate the answer wheel counter-clockwise until the roller 6 enters the wheel notch 4, and separates contacts 11, 13, to break the ninth circuit. After the arrived train leaves track section G, and the track relay M, again is energized by track battery 104, all the mechanisms and parts thereof again have relative normal positions shown in the drawings. As the ninth and tenth circuits pass through the contact 134, and the signal circuit breaker 132, it is obvious that the "two-three" click attest of train arrival at track section G, cannot be obtained by the

train despatcher unless the signal be at normal horizontal adjustment.

If in using the herein-described invention the train despatcher after having "set" the O S relay N, to assure report to him of train arrival at track section G, wishes to annul said relay "setting" and thus allow the train to arrive at said track section and proceed without reporting to him, he may assure such annulment by actuating the key and switch devices E, or an equivalent calling key, to cause operation of the S T group of selector contacts. Operation of the S T contacts establishes the aforesaid eleventh circuit which shifts the selector relay armature 56, against the contact 57, thereby preventing continuous counter-clockwise rotation of answer wheel 1. Operating the S T contacts separates fingers 70, 71, thereby breaking said thirteenth circuit and deenergizing the relay N, and its armatures therefore drop, and armature 111, engages back contact 117, thus establishing the aforesaid ninth circuit which energizes answer-back coil 43, and thus assures counter-clockwise turning of the answer wheel. As the roller 6 now rests in the answer wheel notch 4, the ninth circuit passing through contacts 11, 13, will turn the answer wheel 1, counter-clockwise for only two-thirds of a revolution and still stop when the roller 6 enters the wheel notch 4, and opens contacts 11, 13, to break said ninth circuit. This two-thirds counter-clockwise revolution of the answer wheel will, through the three subjacent pairs of contacts, assure two distinctive "two-three" clicks at the train despatcher's telephone 92, attesting that the prior "setting" of the O S relay N, has been annulled by operation of the S T contacts.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States is:

1. In a signaling system for railroads, a combination of a central station and a way station: a signal sending mechanism adapted to transmit signals to the central station: a signal associated with a way station for exhibiting different aspects to passing trains; a device responsive to the presence of a train on a portion of the track adjacent to the way station; and means controlled from a central station for causing said signal sending mechanism to be selectively subject to control by said signal or said device.

2. In a signaling system for railroads, a

- combination of a central station and a way station: a signal sending mechanism adapted to transmit signals to the central station; a signal associated with a way station for exhibiting different aspects to passing trains and controlled from the central station; a device responsive to the presence of a train on a portion of the track adjacent to the way station; and means selectively controlled from a central station for placing said signal sending mechanism into condition to be automatically controlled by said last mentioned device. 65
3. In a signaling system for railroads, a combination of a central station and a way station: a signal sending mechanism adapted to transmit signals to the central station; a signal associated with a way station for exhibiting different aspects to passing trains and controlled from the central station; a device responsive to the presence of a train on a portion of the track adjacent to the way station; means controlled from a central station for causing said signal sending mechanism to be selectively subject to control by said device to respond to the presence of a train on said portion of track by transmitting a continuous characteristic code signal to the central station; and means controlled from said central station for stopping the continuous operation of said signal sending mechanism. 70
4. In a signaling system for railroads, a combination of a central station and a way station: a signal sending mechanism adapted to transmit signals to the central station; a signal associated with a way station for exhibiting different aspects to passing trains and controlled from the central station; a device responsive to the presence of a train on a portion of the track adjacent to the way station; means selectively controlled from a central station for placing the signal sending mechanism in condition to be automatically controlled by said device to transmit a characteristic code signal to the central station; and means controlled from said central station for verifying said condition. 75
5. In a signaling system for railroads, a combination of a central station and a way station: a signal sending mechanism adapted to transmit signals to the central station; a signal associated with a way station for exhibiting different aspects to passing trains; means associated with the way station and adapted to report to the central station the passage of a train over a portion of the track adjacent to the way station; and means selectively controlled from a central station for placing said signal sending mechanism in condition to be automatically controlled by the operation of said signal to transmit a characteristic code signal to the central station; and means controlled from the central station for verifying the operated condition of said signal. 80
6. In a signaling system for railroads, a combination of a central station and a way station: a signal sending mechanism adapted to transmit signals to the central station; a signal associated with a way station for exhibiting different aspects to passing trains; means adapted to be selectively controlled from the central station and placed in condition to cause operation of the signal sending mechanism upon passage of a train over a portion of the track adjacent to the way station; means controlled from a central station for causing said signal sending mechanism to be selectively subject to control by the operation of said signal and to transmit to the central station a continuous code signal of a distinctive character according to the aspect exhibited; and means controlled from the central station for stopping the continuous operation of said signal sending mechanism. 85
7. In a signaling system for railroads, a combination of a central station and a way station: a signal sending mechanism adapted to transmit signals to the central station; means adapted to be selectively controlled from the central station and placed in condition to cause operation of the signal sending mechanism upon passage of a train over a portion of the track adjacent to the way station; a signal associated with the way station and having a normal biased position and an operated position for exhibiting different aspects to passing trains; means selectively controlled from a central station for causing said signal to be moved from its normal biased position to its operated position; means controlled by said signal in said operated position for causing said signal sending mechanism to transmit to the central station a continuous characteristic code signal of the operated condition of said signal; and means controlled from the central station for stopping the continuous operation of said signal sending mechanism. 90
8. In a signaling system for railroads, a combination of a central station and a way station: a signal associated with a way station for exhibiting different aspects to passing trains; a device responsive to the presence of a train on a portion of the track adjacent to the way station; means controlled from a central station for selectively controlling either said signal or said device; and a signal sending mechanism adapted to transmit signals to the central station and selectively subject to control by said signal or said device. 95
9. In a signaling system for railroads, a combination of a central station and a way station: a signal sending mechanism adapted to

- to transmit signals to the central station; means associated with the way station and adapted to report to the central station the passage of a train over a portion of the track 5 adjacent to the way station; a signal associated with the way station and having a normal biased position and an operated position for exhibiting different aspects to passing trains; means selectively controlled 10 from a central station for causing said signal to be moved from its normal biased position to its operated position; means controlled by said signal in said operated position for causing said signal sending mechanism to 15 transmit to the central station a continuous characteristic code signal of the operated condition of said signal; means controlled from a central station for stopping said continuous operation of said signal sending 20 mechanism; and means operated automatically for causing said signal sending mechanism to transmit to the central station a continuous code signal of a distinctive character from said last mentioned code signal, 25 when said signal is operated abnormally.
10. In a signaling system for railroads, a combination of a central station and a way station: a signal sending mechanism adapted to transmit signals to the central station; 30 means associated with the way station and adapted to report to the central station the passage of a train over a portion of the track adjacent to the way station; a signal associated with the way station and having 35 a normal biased position and an operated position; means for selectively controlling said signal from a central station; means effective in either of said positions of said signal for causing said signal sending mechanism 40 to transmit code signals to the central station which are distinctive in character according to the position of the signal; and means for causing said code signals to be repeated later for the purpose of verifying 45 the condition of said signal, said last mentioned code signal being of a distinctive series from said first mentioned code signals.
11. In a signaling system for railroads, a combination of a central station and a way station: a signal sending mechanism adapted to transmit signals to the central station; a signal associated with a way station for exhibiting different aspects to passing trains and controlled from the central 55 station; a device responsive to the presence of a train on a portion of the track adjacent to the way station; means selectively controlled from a central station for placing said signal sending mechanism into condition to be automatically controlled by said last mentioned device; and other means selectively controlled from the central station for rendering said last mentioned means ineffective.
12. In a signaling system for railroads, a stretch of track provided with a plurality of insulated track circuit sections; a central receiving station, a way station adjacent to each of said track circuit sections; a line circuit extending from the receiving station to the several track circuit sections and way stations; a signal associated with each way station for exhibiting different aspects to passing trains; a device at each way station which is responsive to the presence of a train on the adjacent track circuit section; a signal sending mechanism located at each way station and operable electrically to send a code signal over the line circuit to the receiving station which is distinctive from the similar signals of all of the other mechanisms; and means controlled over the line circuit from the receiving station for causing the signal sending device to be selectively subject to control by said signal or said train responsive device.
13. In a signaling system for railways, a stretch of track provided with a plurality of insulated track circuit sections; a central receiving station, a way station adjacent to each track circuit section, a line circuit extending from the receiving station to the several track circuit sections and way stations, a signal associated with each way station for exhibiting different aspects to passing trains, a device associated with each track circuit section responsive to the presence of a train on its corresponding section, a signal sending mechanism located at each way station and operable electrically to send a plurality of signals over the line circuit to the receiving station, which are distinctive from each other and from the like signals of all the other mechanisms, means controlled over the line circuit from the receiving station for causing the signal sending mechanism to be selectively subject to control by said signal or said train responsive device; and means for automatically selecting the signal to be sent over the line circuit to the receiving station according to the function performed.
14. In a signaling system for railways, a combination of a central station and a way station: a signal sending mechanism adapted to transmit selectively a plurality of distinctive code signals to the central station; a signal associated with a way station for exhibiting different aspects to a passing train; a device responsive to the presence of a train on a portion of track adjacent to the way station; means controlled from a central station for causing said signal sending mechanism to be selectively subject to control by said signal or said train responsive device; and means for automatically selecting the particular code signal to be transmitted to the central station according to the function performed.
15. In a signaling system for railroads,

1. A combination of a central station and a way station; a signal sending mechanism adapted to transmit signals to the central station; a signal associated with a way station for exhibiting different aspects to passing trains and controlled from the central station; a device responsive to the presence of a train on a portion of the track adjacent to the way station; means selectively controlled from a central station for placing said signal sending mechanism into a condition to be automatically controlled by said last mentioned device; other means selectively controlled from the central station for rendering said last mentioned means ineffective; and means automatically controlled for causing said signal sending mechanism to report to the central station, by transmitting a distinctive code signal, the condition of said device after each of said functions has been performed.
2. In a signaling system for railways, in combination: a stretch of track provided with a plurality of insulated track circuit sections; a central receiving station; a way station associated with each track section; a line circuit extending from said central receiving station to said way station; a signal associated with each way station for exhibiting different aspects to passing trains; a track relay associated with each of said track sections and responsive to the presence of a train on its corresponding section; an answer-back located at each way station adapted to transmit code signals over the line circuit to the central station; and a selector located at each way station and controlled from the central station over the line circuit for causing said answer-back to be selectively subject to control by said signal or said track relay.
3. In a signaling system for railroads, a central station, a way station, a take-siding signal for exhibiting different aspects to passing trains and adapted to be controlled from the central station, a track section adjacent to said way station, and means associated with the way station and controlled from the central station for reporting the passage of trains over said track section.
4. In a railway signaling system, a central receiving station, a way station, a line circuit extending from the receiving station to the way station, a take-siding signal associated with the way station for exhibiting different aspects to passing trains, an insulated track section with a track relay associated with the way station, an answer-back mechanism operable to transmit answer-back signals over the line circuit to the central station, and means controlled over the line circuit from the central station for selectively rendering said answer-back mechanism subject to control by the movements of the take-siding signal or the track relay, respectively.
5. In a signaling system for railroads, a central station, a way station, an insulated track section with a track relay associated with the way station, a take-siding signal associated with the way station for exhibiting different aspects to passing trains and adapted to be selectively controlled from the central station, answer-back mechanism located at the way station for transmitting answer-back signals to the central station, and means controlled from the central station for placing said answer-back mechanism into condition to be subject to control by the movements of said take-siding signal or the track relay, respectively.
6. In a signaling system for railroads, a central station, a plurality of way stations, a take-siding signal associated with each way station for exhibiting different aspects to passing trains and adapted to be controlled from the central station, means associated with each way station adapted to be conditioned to transmit distinctive answer-back signals to the central station upon the passage of a train over a portion of track adjacent thereto, and means controlled from the central station for selectively conditioning said means at the several way stations.
7. In a signaling system for railroads, a central station, a way station, an answer-back mechanism adapted to transmit signals to the central station, a take-siding signal associated with the way station for exhibiting different aspects to passing trains and adapted to be controlled from the central station, an O S relay associated with the way station, an energizing circuit for said relay controlled from the central station, an insulated track section with a track relay, said track relay acting to de-energize the O S relay, and means controlled from the central station for causing said answer-back mechanism to be selectively subject to control by the movements of said take-siding signal or said track relay, respectively.
8. In a signaling system for railroads, a central station, a way station, a line circuit extending from the central station to the way station, a take-siding signal for exhibiting different aspects to passing trains and adapted to be controlled over the line circuit from the central station, an O S relay associated with the way station, means controlled over the line circuit from the central station for energizing said O S relay, a track relay responsive to the presence of a train on a portion of the track adjacent to said way station and adapted to de-energize the O S relay, answer-back mechanism operable to transmit answer-back sig-

nals over the line circuit to the central station, and means controlled from the central station for selectively causing said answer-back mechanism to be subject to control by the movements of the take-siding signal or the track relay, respectively.

23. In a railway signaling system, a railroad track provided with a plurality of insulated track sections, a central receiving station, a way station associated with each track section, a line circuit extending from the receiving station to the way stations, a take-siding signal associated with each way station for exhibiting different aspects to passing trains and adapted to be controlled over the line circuit from the central receiving station, a signal sending device at each way station operable electrically to send a code signal over the line circuit to the receiving station which is distinctive from the signals transmitted by all of the other devices, control means for each signal sending device, said control means being normally responsive to the movements of the take-siding signal as it is controlled from the central station, train-responsive means rendered effective by the passage of a train over the corresponding track section, and means selectively controlled over the line circuit from the receiving station for selectively placing said control means at the several way stations under the control of the corresponding train-responsive means instead of its take-siding signal.
24. In a signaling system for railroads, a central station, a way station, an answer-back mechanism adapted to transmit answer-back signals to the central station, a take-siding signal associated with the way station for exhibiting different aspects to passing trains and adapted to be controlled from the central station, an O S relay associated with the way station, an insulated track section with a track relay which acts to de-energize the O S relay, and means selectively controlled from the central station for energizing said O S relay and to cause the answer-back mechanism to be placed into condition to be automatically controlled by said track relay.

25. In a railway signaling system, a central receiving station, a way station, a line circuit extending from the receiving station to the way station, a take-siding signal associated with the way station for exhibiting different aspects to passing trains, a signal relay controlling said take-siding signal, an O S relay, an energizing circuit for each relay controlled by the other relay, means controlled over the line circuit from the central station for selectively controlling said energizing circuits, an insulated track section with a track relay adapted to deenergize the O S relay, and answer-back mechanism

located at the way station and selectively subject to control by said O S relay or said signal relay for transmitting answer-back signals over the line circuit to the central station, whereby a report may be obtained at will at the central station of the positions of the take-siding signal or the passage of a train.

26. In a railway signaling system, a central receiving station, a way station, a line circuit extending from the receiving station to the way station, a take-siding signal associated with the way station for exhibiting different aspects to passing trains, a signal relay controlling the take-siding signal, an insulated track section with a track relay associated with the way station, an O S relay controlled by the track relay, said O S relay and said signal relay being selectively energized from the central station, means for interlocking the energizing circuits for the O S relay and the signal relay, stick circuits for said O S relay and said signal relay selectively controlled from the central station, an answer-back mechanism located at the way station and selectively subject to control by said O S relay or said signal relay for transmitting answer-back signals over the line wires to the central station, whereby conditions may be set up at the way station from the central station at will to report the positions of the take-siding signal or the track relay, respectively, or said conditions can be changed after having been set up.

27. In a railway signaling system, a track provided with a plurality of insulated track sections each having a track relay, a signal sending device associated with each track section, and means controlled from a central station for selectively controlling said signal sending devices to place them respectively in condition to be controlled by the corresponding track relay, each signal sending device operating to send a distinctive answer-back signal to the central station upon being so conditioned, and also to send another distinctive answer-back signal to the central station when the track relay is shunted by the entrance of a train into the corresponding track section.

28. In a railway signaling system, a central receiving station and a plurality of way stations, an insulated track section located at each way station and having a track relay, signal sending means at each way station adapted to transmit a distinctive code signal to the central station, control means for governing the operation of each signal sending means, selectors at the way stations adapted to be selectively controlled from the central station, means controlled by the selector at each way station for changing the normal condition of the corresponding control

means, and means whereby the shunting of the track relay of the corresponding track section by a train causes operation of the signal sending device at a way station when its control means is in its changed condition.

29. In a railway signaling system, a railroad track provided with a plurality of insulated track sections each having a track relay, a central receiving station, a line circuit extending from the central station to the several track sections, a signal sending device associated with each track section and operable to send a distinctive answer-back signal over the line circuit to the central station, which signal is distinctive from the signals transmitted by all of the other devices, control means for each signal sending device adapted when in a particular condition to cause operation of its signal sending device when the corresponding track relay is shunted by the entrance of a train into its track section, and means selectively controlled over the line circuit from the central station for placing the control means at the several track sections respectively into said particular condition, whereby a distinctive answer-back signal may be obtained at the central station whenever desired to tell of the passage of a train over a selected track section.

30. In a railway signaling system, a railroad track provided with a plurality of insulated track sections each having a track relay, a central receiving station, a way station associated with each track section, a line circuit extending from the central station to the several way stations, an electrically operable signal sending device at each way station adapted to transmit either of two distinctive answer-back signals over the line circuit to the central station which are distinctive from each other and from like signals of the other devices, and means selectively controlled over the line circuit from the central station for placing said signal sending devices respectively into condition to be set into operation by the corresponding track relay, each signal sending device when thus conditioned for operation acting automatically to transmit one of its characteristic answer-back signals, and also being rendered responsive to the control of the corresponding track relay to transmit its other

characteristic answer-back signal as soon as a train enters the corresponding track section.

31. In a railway signaling system, a central station, a distant track section, a signal sending device associated with the track section and operable to transmit distinctive answer-back signals to the central station, a take-siding signal and a train reporting mechanism at the track section each adapted to cause operation of the signal sending device, and means for controlling said train reporting mechanism and said take-siding signal selectively from the central station, whereby answer-back signals may be obtained at the central station telling of the setting of the signal or passage of a train.

32. In a railway signaling system, a central station, a plurality of way stations, a track section with a track relay at each way station, a signal at each way station for exhibiting different aspects to passing trains, answer-back mechanism associated with each way station and responsive to the corresponding track relay and signal, and means for selectively controlling said signals from the central station.

33. In a railway signaling system, a central station, a plurality of remote control signals adapted to be governed selectively from the central station, a plurality of distant track sections each having a track relay, and means associated with each track section and adapted to be separately conditioned for operation from the central station for reporting to the central station the passage of a train thereby, said means at each station acting to transmit a distinctive signal characteristic of that station.

34. In a railway signaling system, a railroad track divided into sections, a receiving station, a line circuit extending from said receiving station along said railroad track, a signal sending device associated with each of a plurality of said sections, selectively operated devices controlled over the line circuit from said receiving station for conditioning said signal sending devices for operation, and electric means including closed circuit track portions controlled by train wheels for causing said signal sending devices to send signals over the line circuit to said signal receiving station.

RICHARD C. LEAKE.
